UNITED STATES PATENT OFFICE.

JOSIAH PERCIVAL STEVENS, OF ATLANTA, GEORGIA.

PLATE-PRINTING MACHINE.

SPECIFICATION forming part of Letters Patent No. 764,158, dated July 5, 1904.

Application filed September 30, 1903. Serial No. 175,221. (No model.)

To all whom it may concern:

Be it known that I, JOSIAH PERCIVAL STEVENS, a citizen of the United States, residing at Atlanta, in the county of Fulton and State 5 of Georgia, have invented certain new and useful Improvements in Plate-Printing Machines; and I do hereby declare the following to be a full, clear, and exact description of the invention, such as will enable others skilled in the 10 art to which it appertains to make and use the same.

My present invention relates to presses or machines for printing from engraved plates, and it is intended as an improvement upon the 15 machine described in Letters Patent No. 649,773, granted to me May 15, 1900, and entitled "Plate-printing machine."

According to my present invention the machine has or may have its power self-contained, 20 and thus may be moved from place to place and operated *in situ* without reference to extraneous sources of power. Furthermore, improved means for holding the plate in position are provided, as also for holding the card 25 or sheet to be printed and for readily supplying and removing the same, also to protect the card or sheet from blurring.

It also consists in the improved means for automatically inking the plate and means 30 for adjusting the several parts for use with cards or plates of different sizes.

My invention also consists of certain novel features and constructions and arrangements of parts, which will be hereinafter described 35 and claimed.

Reference is had to the accompanying drawings, in which the same parts are indicated by the same characters throughout the several views.

Figure 1 shows a side elevation of the complete machine. Fig. 2 is an end elevation as seen from that end of the machine carrying the card, at which stands the attendant, hereinafter called the "feeder." Fig. 3 is a plan view, partly in section, along the line 3 3 of Figs. 4 and 5. Fig. 3^a is a detail showing an inverted perspective view of one of the adjustable plate-holders. Fig. 4 shows a section along the line 4 4 of Fig. 3 looking in the 45 direction of the arrows. Fig. 5 shows a sec-

tion along the line 5 5 of Fig. 3 and looking in the direction of the arrows. Figs. 6 and 7 are similar sections to that indicated in Fig. 4, but showing the printing-roller in different positions from that indicated in Fig. 4. Fig. 55 8 is a plan view of the card-carrier detached from the machine. Fig. 9 is an end view of the device shown in Fig. 8 looking toward the top of the sheet. Fig. 10 is a detail showing the spreader-bar for the card-gripper. 60 Fig. 11 is a detail showing the means of adjusting the card-holder. Fig. 12 is a detail showing the releasing-catch of the card-gripper. Fig. 13 is a section along the line 13 13, 65 Fig. 8, and illustrates the action of the card-gripper. Figs. 14 to 19 are details showing means for adjusting the operating-face of the upper printing-roller.

A represents the frame of the machine, which may be of any suitable form, for supporting the several parts of the press, but which in the present instance is shown as consisting of two side frames connected together by the tie-bolts A⁴ and A⁵. These frames are provided with feet A¹ and also with a 70 vertical upper portion A² and brackets A³, to which the table B is secured, as by means of the tie-bolts A⁶. The upper vertical portion is provided with housings A⁶ and A⁷, in which are mounted the journal-bearings for the 75 shafts f and H, as will be hereinafter described.

The table B is preferably provided with vertical sides b and vertical ends b', on which latter the posts B' are secured, as by means of 80 the clamping-screws b². Spanning these posts B' and extending the full length of the table are the guide-rods B³, on which the plate-holder D and the card-holder E slide.

C (see Fig. 3) represents a pulley secured to 90 the post B³, over which pulley passes the strap C', connected at one end to the weight C² and at the other to the plate-carrier D, and thus this weight tends to return the plate-carrier to the position indicated in Fig. 3 at the end 95 of each cycle of operations. This end of the machine we will call the "operator's" end and the other end the "feeder's" end for convenience of description.

The plate-carrier consists of a bed-plate D, 100

which is mounted to slide along the rods B³ and at the end of its travel toward the "operator" engages the sleeve b³, (see Fig. 3,) which bears against the spring b⁴, and thus the 5 sleeve and spring act as a buffer to check the backward movement of the plate-carrier. The bed-plate D is provided with sockets, in which the lugs d² from the plate-holder D² project. The plate-holder carries two fixed 10 stops d for holding one end of the plate and two adjustable stops d', projecting from the groove d⁰ in the plate-holder, (see Fig. 3,) for the other end of the plate. These stops d' are adjusted by means of the screws D⁰. I 15 provide a series of plate-holders of different sizes, so that plates of different sizes may be mounted on the same machine without excessive adjustment of the stops d'. It will be seen that the plate-holder D² may be readily 20 removed and a larger or smaller put in place without otherwise interfering with the action of the machine, and this may be very quickly done.

The means by which the plate-carrier and 25 card-carrier are coupled together and the two are moved together during the operation of printing cards and then automatically released and restored to the initial position at each end of the machine can better be described after 30 explaining other parts of the mechanism.

F represents the lower printing-roller, which is mounted on the shaft f, journaled in fixed bearings f' at the lower end of the housings A⁶. The upper printing-roller N is fixed 35 on the shaft H, which shaft carries the clutch member H' and spring H² for throwing the same into engagement with the clutch member G' on the hub of the wheel G, which is mounted loose on the shaft H. This wheel G 40 is at once the drive-wheel and fly-wheel of the machine, and it is driven by means of a belt M, which passes over idlers M² to the driving-pulley M³ on the electric motor M'. The connections for the electric motor not being a 45 part of my invention are omitted from the drawings for the sake of clearness.

I preferably drive the machine by means of an electric motor, so that it may be located in any convenient place in the factory and 50 driven by feed-wires from any suitable source of current; but, if preferred, the wheel G may be driven by means of a belt from any line of shafting or by any suitable gearing. The wheel G is normally kept continuously in rotation while the machine is being used; but the shaft H only turns with the wheel G when the clutch members H' and G' are in engagement. These clutch members are normally kept apart by means of the wedge K, which 55 projects between the clutch members and is held up in position by means of the spring K², mounted on the bracket K³, fast to the frame A. The rod K' passes through the spring K² and is connected by the link K⁴ to the lever 60 K⁵, which lever is connected by the rod K⁶ to

the treadle L, which is pivoted to the frame, as at L', and is provided with a shoe-piece L². Thus it will be seen that by pressing down on this shoe-piece the wedge K is withdrawn, and the spring H² throws the clutch members G' 70 and H' into engagement and causes the shaft H to rotate with the wheel G. Any suitable clutch-operating mechanism may be used—such, for instance, as that shown in my Patent No. 649,773, aforesaid. 75

The ends of the shaft H are journaled in journal-bearings h in the housing A⁷. These journal-bearings are pressed upward by the springs J and are adjusted downward by means of the screws I, projecting into sockets 80 h on the upper member of the journal-bearing h', as shown in Fig. 1. By means of these screws the distance between the compression-surfaces of the upper and lower printing-rollers may be adjusted to suit various thicknesses of plate. The upper printing-roller N is cut away on one side, as indicated in Figs. 4 to 6, and the cylindrical portion may be covered with several layers of paper n, held in place by the spring N', whose ends abut 85 against the shoulders n', and thus bind the paper in place, as described in my Patent No. 649,773; but the operating-face of the upper printing-roller is preferably constructed as shown in Figs. 14 to 17, in which N³ represents a block in the form of a segment of a cylinder and provided with flanges N⁴ and N⁵, as shown in Fig. 16, over which flanges the hooks N⁶ engage. These hooks are pivoted in the roller N, fast on the shaft H. Pins N⁷ 100 project from the roller N and engage in sockets n⁶ in the block N³, as shown in full lines in Fig. 17 and in dotted lines in Figs. 18 and 19. Over the face of the block N³ is mounted 105 a plate n³, of brass or other suitable metal, whose ends are secured to the shoulders of the block, as at n⁴, Figs. 18 and 19. By having a series of these blocks N³ of different lengths circumferentially, the operating-face of the upper printing-roller may be adjusted to correspond to the size of the plate on the plate-holder. 110

Three sizes of the block N³ are shown in Figs. 14, 18, and 19; but the number may be increased indefinitely. It will be seen that 115 these blocks N³ may be readily and quickly applied to and removed from the roller N, and thus by shifting the plate-holder and the impression-block N³ on the upper roller the machine will be readily adjusted for any desired size of plate. 120

Loosely mounted on the shaft H is the oscillating ink-roller frame, which comprises the hub O², from which projects two arms O' and O³, set at an obtuse angle. The arm 125 O' carries the inking-roller O, while the arm O³ is connected by the cord or strap O⁵, passing over the pulley O⁶ to the arm O⁷, operated by a coil-spring in the box O⁸. (See Figs. 1 and 5.) The tendency of this spring- 130

controlled arm O^7 is to hold the arm O^3 in the position indicated in full lines in Fig. 5, with the ink-roller O pressed against the ink-distributing roller P . The ink-roller O is preferably made of a series of rings or disks of Canton flannel or like material, as is well known in the art. This ink-distributing roller P is mounted on a shaft P' , which carries a gear-wheel P^2 , meshing with the pinion Q on the shaft Q' , which shaft carries the gear-wheel Q^2 , meshing with the pinion G^3 on the hub of the wheel G . Thus the rotation of the wheel G will rotate the shaft P' and will cause the roller P to rotate the ink-roller O . The ink T , in the ordinary pasty form, is held between the guards R^2 in front of the board R , which carries a spreader R' , adjusted by means of the straps r and screws r' . Behind this spreader is the ink-distributing roller S , which preferably has a longitudinal as well as a rotary motion in the manner well known in the art and which serves to evenly distribute the ink on the roller P .

The card-carrier E carries the downwardly-projecting arm 1 , to which is attached the cord U , which passes over the pulley U' , mounted in a hanger U^2 , secured to one of the rods B^3 . This cord U is connected to an arm U^3 , which is normally under stress from the coil-spring in the box U^4 . (See Fig. 2.) The tendency of this spring is to draw the card-carriage toward the plate-carriage, and when this spring is allowed to act the coupling 2 on the card-carriage snaps over the hook d^4 on the plate-carrier, and the two are coupled together. The card-carrier is held in the initial position at the feeder's end of the machine by means of the stop v on the spring-catch V , which is normally pressed upward, as shown in Fig. 4, by means of the spring V' . This spring-catch is drawn down by the cord V^2 when it is desired to release the card-carrier, and the latter is then impelled by means of the cord U^4 toward the plate-carrier. This cord V^2 is connected to the lever V^3 , which is suspended, as at V^4 , from one of the tie-bolts A^4 , and this lever is connected by means of the rod V^5 to the treadle W , which is pivoted, as at W' , to the treadle L . This treadle W has a lug W^2 , which projects through a hole in the shoe L^2 of the treadle L , so that the pressure of the foot of the operator will cause the treadle W to pull down the rod V^5 and release the card-carrier before the treadle L , withdrawing the wedge K from between the members G^2 and H^2 of the coupling on the shaft H . The hook d^4 is on a spring-plate D^4 , secured to the card-carrier, as by screws D^6 , (see Figs. 4, 6, and 7,) and the forward end of this plate is curved, as at d^5 , to strike the pin X and withdraw the hook B^4 from engagement with the coupling 2 of the card-carrier when the plate-carrier has reached the limit of its travel. (See Fig. 7.) At this time the card-carrier is held by the arm 1 engag-

ing the catch v , while the plate-carrier is free to return to the initial position under the action of the weight C^2 .

When the card-carrier is coupled to the plate-carrier, the card or sheet to be printed will be in the proper position over the plate and will be moved to the right between the printing-rollers in the manner that will now be described.

The bar D^6 is adjustably secured to the side of the plate-carrier, as by means of the clamp-screws d' , and this bar carries a boss D^5 , which is engaged by a roller Y' on the arm Y , which is adjustably connected to the upper printing-roller N by clamp-screws, as shown in Figs. 4, 6, and 7. When the parts are in the initial position, (shown in Fig. 4,) suppose the operator presses with his foot on the shoe L^2 , the first motion of his foot will press down the stud W^2 , releasing the card-carrier and allowing it to fly over to and couple with the plate-carrier. A further motion of the foot will press the shoe L^2 down, removing the wedge K from the coupling and transmitting the motion of the wheel G to the shaft H and to the printing-roller N fast thereon. As the printing-roller revolves the roller Y' will engage the lug D^5 , pushing the two carriages, which are coupled together, to the right against the action of the weight C^2 . Before the roller Y' passes clear of the boss D^5 the plate D^3 and the plate-holder D^2 , with the bed supporting the same, are firmly gripped between the surfaces of the upper and lower printing-rollers, and the plate-carrier is pushed on through until the rotation of the upper printing-roller N causes the rounded surface to pass clear of the plate, as indicated in Fig. 7. At this time the plate-carrier is automatically uncoupled from the card-carrier, as before described, and the plate-carrier returns to its initial position under the action of the weight C^2 , while the card-carrier is held in the initial position by the catch v .

During the cycle of operations just described the inking mechanism is put into action, as will now be explained. When the card-carrier and the plate-carrier are in the initial or separated position, as shown in Fig. 5, the ink-roller O will be up against the distributing-roller P and the arm O^3 will project downward in the position indicated by the full lines in Fig. 5. Soon after the plate-carrier is started from the initial position in the manner hereinbefore described the roller D^7 , which is fast to a plate D^8 , adjustably connected to a side of the plate-carrier, engages the upper face of the arm O^3 and rolls along the same, at the same time rocking the hub O^2 about the shaft H . Before the plate-carrier will reach the limit of its travel the ink-roller will be rocked down to the position indicated in dotted lines in Fig. 5, until finally the stud O^4 on the arm O^3 will pass in front of the catch Z' on the spring-bar Z ,

which is adjustably connected, as by means of the screws z and z' , to the table B. This catch Z' will spring up in front of the stud O^4 and will lock the arm O^3 in the position indicated by the dotted lines in Fig. 5 until the plate-carriage returns almost to the initial position. Just before the plate reaches the initial position the curved end b^9 of the bar D^9 , which is secured to the plate-carrier, as shown in Fig. 5, will ride up over the curved end Z^2 of the spring-bar Z and will press the catch Z' out of engagement with the roller O^4 , allowing the cord O^5 to swing the inking-roller back to the initial position. (Shown in full lines in Fig. 5.)

The manner of inserting and removing the card or sheet to be printed from the card-carrier and of operating the card-carrier will now be described.

In the initial position the card-carrier will be at the end of the machine next the feeder, as shown in Figs. 1, 3, 4, and 5, with the catch v engaging the arm 1, holding the carrier against the action of the cord U, as indicated in Fig. 4.

The card-carrier consists, essentially, of two members a bed and a card-gripper pivoted on said bed, with means for swinging said card-gripper laterally about its pivot and means for moving the card-gripper transversely, whereby the card-gripper may be accurately adjusted to receive the card and to hold it in the proper position and to carry it above the plate when the card-carrier is released.

The bed of the card-carrier is provided with two arms E^2 and E^3 , with downwardly-projecting flanges 7 and 7^a , which flanges are perforated to pass over one of the guide-rods B^3 . Near the extremities of the arms E^2 and E^3 are feet e , which slide over the other guide-rod B^3 , so that the carriage slides freely on the two guide-rods B^3 .

The card-gripper is mounted on an L-shaped frame E' , which is pivoted on the pin e^2 , which pin slides in the slot in the bed of the carriage, (shown in dotted lines in Fig. 8,) and the said pin is transversely perforated to receive the screw-thread e' , which is turned by the milled head e^3 and is provided with a ratchet e^4 and a spring-pawl e^5 , so that the screw e' may be held in the desired position without turning when the carriage is vibrated backward and forward in the ordinary operation of printing. This screw e' provides a transverse adjustment for the gripper relative to the carriage, while the gripper may be turned through a small angle by means a similar screw e^6 , passing through a pin e^7 , projecting through the slot e^8 in the arm E^2 , which screw is locked fast by the ratchet e^9 and spring-pawl e^9 .

For convenience of reference I have indicated all the parts for giving transverse adjustment to the gripper by E' and all the parts for swinging the gripper through a small angle by E^2 .

The coupler-head 2 is mounted on a rod 3, which is adjusted by means of the milled head 4, fast thereon, and the screw-threads 5, which mesh in the nut 6, fast to or integral with the flange 7. (See Fig. 9.) This rod 3 may be held against turning in any convenient way, as by means of a bent pin 9 passing through one of the holes 8 provided in the rod and connected at its upper end to the bed of the carrier.

E^6 represents a sliding spreader-bar having two wedge-faces 11 and 12 on its lower side, a notch 14 on its upper side, and a bent arm 13, with a flat upper face 15, as shown in detail in Fig. 10. This spreader-bar passes under two spring-gripping plates E^9 , which are riveted to one arm of the gripper-frame, as at 18. The stem 17 of these gripper-plates is resilient, while the holding parts are broad, as at 16, so as not to disfigure the card. These plates are riveted to the bar 19, as shown in Fig. 13, and project over the inclined card-holding recess 21 in the bar 20.

The bars 19 and 20 are connected by the cross-pieces 22, and the spreader-bar E^6 slides above the cross-pieces 22 in the slot between the bars 19 and 20. The spring E^7 tends to withdraw the spreader-bar E^6 ; but the latter is normally held by means of the spring-catch E^{11} . This catch E^{11} (shown in detail in Fig. 12) carries a lip 23, under which the tripper E^8 engages. This tripper is pivoted at 25 to the gripper-frame and terminates in a button 26, which is so spaced that it may be struck by the wrist of the feeder when she has inserted the card. As soon as she has inserted the card she presses on this button 26, which causes the spring E^7 to retract the spreader E^6 , and the click of the parts gives a signal to the operator that all is ready at the feeder's end for the machine to be started.

The gripper-bar is automatically operated, when the card-carrier nears the limit of its forward travel, by means of the bar B^5 , which is fast to the table B and strikes the arm 13 of the spreader-bar E^6 just before the card-carrier reaches the extreme limit of its forward travel, being pressed forward by the action of the printing-rollers. As soon as the upper printing-roller revolves clear of the card the weight C^2 pulls the two carriages still coupled together backward; but after the card-carrier has moved a short distance backward it is automatically uncoupled from the plate-carrier, as before described, and is locked in the initial position. This short back travel of the card-carrier affords play enough for the arm 13 of the spreader-bar E^6 , so that when the bar is released the spring E^7 can retract it far enough before it strikes the end of the bar B^5 to withdraw the wedges from beneath the gripping-plates E^9 , allowing the parts 16 of these plates to spring down over and to hold the edge of the card, as shown in Fig. 13.

By having the groove 21 in the bar 20 in-

clined, as shown in Fig. 13, the stiffness of the card E^9 or of the sheet of paper to be printed will cause the card or sheet to tilt up, as shown in Fig. 13, and thus the card slides 5 above the plate when the two carriages come together, and the resiliency of the card or sheet causes it to spring up again after the printing-roller has passed over it, thus allowing the plate to be withdrawn from under the 10 still moist ink adhering to the card without smearing. This is especially important not only in securing better work, but also in saving the time required to pick up the cards from the plate without smearing.

15 I have shown two bars 19 and 20; but it will be obvious that a single bar with a slot in the center may be used instead of the two bars, if desired.

It will be seen that nearly all the parts are 20 made adjustable to provide for the exceedingly nice and accurate work required of a machine of this character; but many of these adjustments may be omitted, and the adjusting means may be varied at will.

25 Having thus described the coaction and operation of the several parts, I will state briefly the operation of the entire machine.

Suppose the wheel G to be running, but the shaft H to be still and the card-carrier and 30 the plate-carrier to be in the initial position. (Indicated in Fig. 3.) When the operator presses down on the shoe L², the pressure on the stud W² will release the card-carrier, which will fly forward and automatically couple to 35 the plate-carrier; but at the first operation of the series there need be no card in the carrier, as the plate will not be inked. A further downward pressure of the foot of the operator will cause the treadle L to withdraw the 40 wedge K and will cause the shaft H to couple onto the wheel G. This will turn the printing-roller N, causing the arm Y to push the plate-holder D², with the plate D³ thereon, beneath the said printing-roller, and it will be 45 pushed on through between the upper and lower printing-rollers, as before described. At the same time the ink-roller O will be brought down to the position indicated by dotted lines in Fig. 5. As soon as the upper 50 roller N revolves clear of the plate the plate-carrier will be drawn back by the weight C², leaving the card-carrier behind, as already described. The plate will pass under the inking-roller and will be inked thereby, and after 55 passing under the said roller the arm O³ will be released, allowing the cord O⁶, with the spring for operating the same, to swing the ink-roller O back to the position indicated by full lines in Fig. 5. The back travel of the 60 plate-carrier will be limited by the buffer b³, while the card-carrier will be held by the catch v. The card-carrier will be pushed far enough forward in the machine to cause the bar B⁵ to press on the arm 13 of the spreader-bar E⁶,

causing the wedges 11 and 12 to spread the 65 gripper open for the reception of the edge of a card, this against the action of the spring E⁷. The spreader-bar is held in this position by means of the spring-catch E¹¹. While the operator at his end of the machine gets the 70 plate ready, the feeder at her end of the machine is inserting the card in the gripper. As soon as the card is in place she presses, preferably with her wrist, on the button 26, which releases the spring-catch E¹¹ and allows 75 the spring E⁷ to pull the gripper-bar E⁶ back, causing the gripping-plates E⁹ to grip the card, as shown in Fig. 13. The operator hears the click caused by the motion of the spreader-bar E⁶ and knows that the card or sheet is in 80 place for printing. As soon as he hears this click, which will be about the same time he will have the plate ready, he presses on the treadles, as before, with the result that the treadle W first releases the card-carrier and 85 allows it to fly back and couple onto the plate-carrier, while immediately thereafter the treadle L withdraws the wedge K and allows the wheel G to rotate the upper printing-roller N through a single revolution. The card now 90 being over the plate and the latter inked is duly printed when it passes between the two printing-rollers, and after being clear of the upper roller N the resiliency of the card causes 95 it to tilt up slightly, as indicated in Fig. 13, thus raising its inked surface clear of the face of the plate. The final forward movement of the two carriages coupled together will cause the spreader-bar to spread the grippers and the attendant takes the card out. Just as the 100 grippers are spread the plate-carrier is automatically uncoupled from the card-carrier and is drawn backward by the weight C² and the feeder removes the card and substitutes another one. The cycle of operations may be 105 repeated indefinitely.

By having removable plate-holders of different sizes the plates may be readily fitted on the machine, whether for printing cards or sheets, and the card-carrier is also provided 110 with adjustments for readily adjusting the parts to the required conditions.

It will be obvious that various modifications might be made in the herein-described apparatus which could be used without departing 115 from the spirit of my invention.

Having thus described my invention, what I claim, and desire to secure by Letters Patent of the United States, is—

1. In a plate-printing machine, the combination with a frame, a lower printing-roller journaled thereon, and an upper printing-roller in the form of a segment of a cylinder mounted above said lower printing-roller, of a plate-carrier mounted to vibrate on said 120 frame between said rollers, and a card-carrier, with means for automatically moving same 125 toward and coupling same to said plate-car-

rier, and for uncoupling same and holding the card-carrier in the initial position until released, substantially as described.

2. In a plate-printing machine, the combination with a frame, a lower printing-roller journaled thereon, and an upper printing-roller in the form of a segment of a cylinder mounted above said lower printing-roller, of a plate-carrier mounted to vibrate on said frame between said rollers, and a card-carrier, with means for automatically moving same toward and coupling same to said plate-carrier, and for uncoupling same and holding the card-carrier in the initial position until released, with means for holding the card normally at an angle on said card-carrier and causing it to project above and clear of the plate, except when pressed between the rollers, substantially as described.
3. In a plate-printing machine, the combination with a frame, a lower printing-roller journaled thereon, and an upper printing-roller in the form of a segment of a cylinder mounted above said lower printing-roller, of a plate-carrier mounted to vibrate on said frame between said rollers, and a card-carrier, with means for automatically moving same toward and coupling same to said plate-carrier, and for uncoupling same and holding the card-carrier in the initial position until released, and an ink-roller automatically operated by the motion of said plate-carrier for inking the plate, substantially as described.

4. In a plate-printing machine, the combination with a frame, a lower printing-roller journaled thereon, and an upper printing-roller in the form of a segment of a cylinder mounted above said lower printing-roller, of a plate-carrier mounted to vibrate on said frame between said rollers, and a card-carrier, with means for automatically moving same toward and coupling same to said plate-carrier, and for uncoupling same and holding the card-carrier in the initial position until released, with means for holding the card normally at an angle on said card-carrier and causing it to project above and clear of the plate, except when pressed between the rollers, and an ink-roller automatically operated by the motion of said plate-carrier for inking the plate, substantially as described.

5. In a plate-printing machine, the combination with a frame, a lower printing-roller journaled thereon, and an upper printing-roller mounted above said lower printing-roller, with a removable shell in the form of a segment of a cylinder secured upon said upper printing-roller, of a plate-carrier mounted to vibrate on said frame between said rollers, an adjustable plate-holder mounted on said carrier, and a card-carrier, with means for automatically moving same toward and coupling same to said plate-carrier, and for uncoupling same and holding the card-carrier in

the initial position until released, substantially as described.

6. In a plate-printing machine, the combination with a frame, a lower printing-roller journaled thereon, and an upper printing-roller mounted above said lower printing-roller, with a removable shell in the form of a segment of a cylinder secured upon said upper printing-roller, of a plate-carrier mounted to vibrate on said frame between said rollers, an adjustable plate-holder mounted on said carrier, and a card-carrier, with means for automatically moving same toward and coupling same to said plate-carrier, and for uncoupling same and holding the card-carrier in the initial position until released, with means for holding the card normally at an angle on said card-carrier and causing it to project above and clear of the plate, except when pressed between the rollers, substantially as described.

7. In a plate-printing machine, the combination with a frame, a lower printing-roller journaled thereon, and an upper printing-roller mounted above said lower printing-roller, with a removable shell in the form of a segment of a cylinder secured upon said upper printing-roller, of a plate-carrier mounted to vibrate on said frame between said rollers, an adjustable plate-holder mounted on said carrier, and a card-carrier, with means for automatically moving same toward and coupling same to said plate-carrier, and for uncoupling same and holding the card-carrier in the initial position until released, and an ink-roller automatically operated by the motion of said plate-carrier for inking the plate, substantially as described.

8. In a plate-printing machine, the combination with a frame, a lower printing-roller journaled thereon, and an upper printing-roller mounted above said lower printing-roller, with a removable shell in the form of a segment of a cylinder secured upon said upper printing-roller, of a plate-carrier mounted to vibrate on said frame between said rollers, an adjustable plate-holder mounted on said carrier, and a card-carrier, with means for automatically moving same toward and coupling same to said plate-carrier, and for uncoupling same and holding the card-carrier in the initial position until released, with means for holding the card normally at an angle on said card-carrier and causing it to project above and clear of the plate, except when pressed between the rollers, and an ink-roller automatically operated by the motion of said plate-carrier for inking the plate, substantially as described.

9. In a plate-printing machine, the combination with a frame, a lower printing-roller journaled thereon, and an upper printing-roller mounted above said lower printing-roller, with a removable shell in the form of

a segment of a cylinder secured upon said upper printing-roller, of a plate-carrier mounted to vibrate on said frame between said rollers, a removable and adjustable plate-holder 5 mounted on said carrier, and a card-carrier, with means for automatically moving same toward and coupling same to said plate-carrier, and for automatically uncoupling same and holding the card-carrier in the initial position 10 until released, substantially as described.

10. In a plate-printing machine, the combination with a frame, a lower printing-roller journaled thereon, and an upper printing-roller mounted above said lower printing- 15 roller, with a removable shell in the form of a segment of a cylinder secured upon said upper printing-roller, of a plate-carrier mounted to vibrate on said frame between said rollers, a removable and adjustable plate-holder 20 mounted on said carrier, and a card-carrier, with means for automatically moving same toward and coupling same to said plate-carrier, and for automatically uncoupling same and holding the card-carrier in the initial position 25 until released, with means for holding the card normally at an angle on said card-carrier and causing it to project above and clear of the plate, except when pressed between the rollers, substantially as described.

30 11. In a plate-printing machine, the combination with a frame, a lower printing-roller journaled thereon, and an upper printing-roller mounted above said lower printing-roller, with a removable shell in the form of 35 a segment of a cylinder secured upon said upper printing-roller, of a plate-carrier mounted to vibrate on said frame between said rollers, a removable and adjustable plate-holder mounted on said carrier, and a card-carrier, 40 with means for automatically moving same toward and coupling same to said plate-carrier, and for automatically uncoupling same and automatically holding the card-carrier in the initial position until released, and an ink-roller 45 automatically operated by the motion of said plate-carrier for inking the plate, substantially as described.

12. In a plate-printing machine, the combination with a frame, a lower printing-roller 50 journaled thereon, and an upper printing-roller mounted above said lower printing-roller, with a removable shell in the form of a segment of a cylinder secured upon said upper printing-roller, of a plate-carrier mounted 55 to vibrate on said frame between said rollers, a removable and adjustable plate-holder mounted on said carrier, and a card-carrier, with means for automatically moving same toward and coupling same to said plate-carrier, 60 and means for automatically uncoupling same and holding the card-carrier in the initial position until released, with means for holding the card normally at an angle on said card-carrier and causing it to project above and 65 clear of the plate, except when pressed be-

tween the rollers, and an ink-roller automatically operated by the motion of said plate-carrier for inking the plate, substantially as described.

13. In a plate-printing machine, the combination with a frame, a lower printing-roller journaled thereon, and an upper printing-roller in the form of a segment of a cylinder mounted above said lower printing-roller, of a plate-carrier mounted to vibrate on said 70 frame between said rollers, and a card-carrier, with means for automatically moving same toward and coupling same to said plate-carrier, means for automatically uncoupling same when it returns to the initial position, and automatic means for holding the card-carrier in the initial position until released, substantially as described.

14. In a plate-printing machine, the combination with a frame, a lower printing-roller 85 journaled thereon, and an upper printing-roller in the form of a segment of a cylinder mounted above said lower printing-roller, of a plate-carrier mounted to vibrate on said frame between said rollers, and a card-carrier, 90 with means for automatically moving same toward and coupling same to said plate-carrier, means for automatically uncoupling same when it returns to the initial position, and automatic means for holding the card-carrier in 95 the initial position until released, with means for holding the card normally at an angle on said card-carrier and causing it to project above and clear of the plate, except when pressed between the rollers, substantially as 100 described.

15. In a plate-printing machine, the combination with a frame, a lower printing-roller journaled thereon, and an upper printing-roller in the form of a segment of a cylinder 105 mounted above said lower printing-roller, of a plate-carrier mounted to vibrate on said frame between said rollers, and a card-carrier, with means for automatically moving same toward and coupling same to said plate-carrier, 110 means for automatically uncoupling same when it returns to the initial position, and automatic means for holding the card-carrier in the initial position until released, and an ink-roller 115 automatically operated by the motion of said plate-carrier for inking the plate, substantially as described.

16. In a plate-printing machine, the combination with a frame, a lower printing-roller journaled thereon, and an upper printing-roller in the form of a segment of a cylinder mounted above said lower printing-roller, of a plate-carrier mounted to vibrate on said frame between said rollers, and a card-carrier, 120 with means for automatically moving same toward and coupling same to said plate-carrier, means for automatically uncoupling same when it returns to the initial position, and automatic means for holding the card-carrier in the initial position until released, with means 125 130

for holding the card normally at an angle on said card-carrier and causing it to project above and clear of the plate, except when pressed between the rollers, and an ink-roller automatically operated by the motion of said plate-carrier for inking the plate, substantially as described.

17. In a plate-printing machine, the combination with a frame, a lower printing-roller journaled thereon, and an upper printing-roller mounted above said lower printing-roller, with a removable shell in the form of a segment of a cylinder secured upon said upper printing-roller, of a plate-carrier mounted to vibrate on said frame between said rollers, an adjustable plate-holder mounted on said carrier, and means for feeding the card to the plate, substantially as described.

18. In a plate-printing machine, the combination with a frame, a lower printing-roller journaled thereon, and an upper printing-roller mounted above said lower printing-roller, with a removable shell in the form of a segment of a cylinder secured upon said upper printing-roller, of a plate-carrier mounted to vibrate on said frame between said rollers, an adjustable plate-holder mounted on said carrier, and a card-carrier, with means for automatically moving same toward and coupling same to said plate-carrier, and for uncoupling same and holding the card-carrier in the initial position until released, with a spring-gripper for holding the card normally at an angle on said card-carrier and causing it to project above and clear of the plate, except when pressed between the rollers, substantially as described.

19. In a plate-printing machine, the combination with a frame, a lower printing-roller journaled thereon, and an upper printing-roller mounted above said lower printing-roller, with a removable shell in the form of a segment of a cylinder secured upon said upper printing-roller, of a plate-carrier mounted to vibrate on said frame between said rollers, an adjustable plate-holder mounted on said carrier, means for automatically feeding the card to the plate, and an ink-roller automatically operated by the motion of said plate-carrier for inking the plate, substantially as described.

20. In a plate-printing machine, the combination with a frame, a lower printing-roller journaled thereon, and an upper printing-roller mounted above said lower printing-roller, of a plate-carrier mounted to vibrate on said frame between said rollers, a plate-holder mounted on said carrier, a card-carrier, and means for holding the card normally at an angle on said card-carrier and causing it to project above and clear of the plate, except when pressed between the rollers, and an ink-roller automatically operated by the motion of said plate-carrier for inking the plate, substantially as described.

21. In a plate-printing machine, the combination with a frame, a lower printing-roller journaled thereon, and an upper printing-roller mounted above said lower printing-roller, of a plate-carrier mounted to vibrate on said frame between said rollers, a plate-holder mounted on said carrier, a card-carrier, and means for holding the card at an angle above said carrier, substantially as and for the purposes described.

22. In a plate-printing machine, the combination with a frame, a lower printing-roller journaled thereon, and an upper printing-roller mounted above said lower printing-roller, of a plate-carrier mounted to vibrate on said frame between said rollers, a plate-holder mounted on said carrier, a card-carrier, and a spring-gripper for holding the card at an angle above said carrier, substantially as and for the purposes described.

23. In a plate-printing machine, the combination with a frame, a lower printing-roller journaled thereon, and an upper printing-roller mounted above said lower printing-roller, with a removable shell in the form of a segment of a cylinder secured upon said upper printing-roller, of a plate-carrier mounted to vibrate on said frame between said rollers, a removable and adjustable plate-holder mounted on said carrier, and a card-carrier, with means for automatically moving same toward and coupling same to said plate-carrier, and for automatically uncoupling same and holding the card-carrier in the initial position until released, with a spring-gripper holding the card normally at an angle on said card-carrier and causing it to project above and clear of the plate, except when pressed between the rollers, substantially as described.

24. In a plate-printing machine, the combination with a frame, a lower printing-roller journaled thereon, and an upper printing-roller mounted above said lower printing-roller, of a plate-carrier mounted to vibrate on said frame between said rollers, a removable and adjustable plate-holder mounted on said carrier, and a card-carrier, with means for automatically moving same toward and coupling same to said plate-carrier, and for automatically uncoupling same and holding the card-carrier in the initial position until released, with a spring-gripper holding the card normally at an angle on said card-carrier and causing it to project above and clear of the plate, except when pressed between the rollers, substantially as described.

25. In a plate-printing machine, the combination with a frame, a lower printing-roller journaled thereon, and an upper printing-roller mounted above said lower printing-roller, with a removable shell in the form of a segment of a cylinder secured upon said upper printing-roller, of a plate-carrier mounted to vibrate on said frame between said rollers, a removable and adjustable plate-holder

mounted on said carrier, and a card-carrier, with means for automatically moving same toward and coupling same to said plate-carrier, and for automatically uncoupling same and automatically holding the card-carrier in the initial position until released, with a spring-gripper holding the card normally at an angle on said card-carrier and causing it to project above and clear of the plate, and an ink-roller automatically operated by the motion of said plate-carrier for inking the plate, substantially as described.

26. In a plate-printing machine, the combination with a frame, a lower printing-roller journaled thereon, and an upper printing-roller mounted above said lower printing-roller, of a plate-carrier mounted to vibrate on said frame between said rollers, a plate-holder mounted on said carrier, and a card-carrier, with means for automatically moving same toward and coupling same to said plate-carrier, and means for automatically uncoupling same and holding the card-carrier in the initial position until released, with means for holding the card normally at an angle on said card-carrier and causing it to project above and clear of the plate, except when pressed between the rollers, and means for inking the plate, substantially as described.

30 27. In a plate-printing machine, the combination with a frame, a lower printing-roller journaled thereon, and an upper printing-roller mounted above said lower printing-roller, of a plate-carrier mounted to vibrate on said frame between said rollers, a plate-holder mounted on said carrier, and a card-carrier, with means for automatically moving same toward and coupling same to said plate-carrier, and means for automatically uncoupling same and holding the card-carrier in the initial position until released, with a spring-gripper for holding the card normally at an angle on said card-carrier and causing it to project above and clear of the plate, except when pressed between the rollers, and means for inking the plate, substantially as described.

28. In a plate-printing machine, the combination with a frame, a lower printing-roller 50 journaled thereon, and an upper printing-roller in the form of a segment of a cylinder mounted above said lower printing-roller, of a plate-carrier mounted to vibrate on said frame between said rollers, and a card-carrier, with means for automatically moving same toward and coupling same to said plate-carrier, means for automatically uncoupling same when it returns to the initial position, and automatic means for holding the card-carrier in the initial position until released, with means for holding the card inclined upward at an angle on the card-carrier, substantially as described.

29. In a plate-printing machine, the combination with a frame, a lower printing-roller

journaled thereon, and an upper printing-roller in the form of a segment of a cylinder mounted above said lower printing-roller, of a plate-carrier mounted to vibrate on said frame between said rollers, and a card-carrier, 70 with means for automatically moving same toward and coupling same to said plate-carrier, means for automatically uncoupling same when it returns to the initial position, and automatic means for holding the card-carrier in the initial position until released, with a spring-gripper for holding the card inclined upward at an angle on the card-carrier, substantially as described.

30. In a plate-printing machine, the combination with a frame, a lower printing-roller journaled thereon, and an upper printing-roller mounted above said lower printing-roller, of a plate-carrier mounted to vibrate on said frame between said rollers, and a card-carrier, with means for automatically moving same toward and coupling same to said plate-carrier, means for automatically uncoupling same when it returns to the initial position, and automatic means for holding the card-carrier in the initial position until released, with means for holding the card normally at an angle on said card-carrier and causing it to project above and clear of the plate, except when pressed between the rollers, substantially as described.

31. In a plate-printing machine, the combination with a frame, a lower printing-roller journaled thereon, and an upper printing-roller mounted above said lower printing-roller, of a plate-carrier mounted to vibrate on said frame between said rollers, and a card-carrier, with means for automatically moving same toward and coupling same to said plate-carrier, means for automatically uncoupling same when it returns to the initial position, and automatic means for holding the card-carrier in the initial position until released, with a spring-gripper for holding the card normally at an angle on said card-carrier and causing it to project above and clear of the plate, except when pressed between the rollers, substantially as described.

32. In a plate-printing machine, the combination with a frame, a lower printing-roller 115 journaled thereon, and an upper printing-roller mounted above said lower printing-roller, of a plate-carrier traveling on said frame between said rollers, and a card-carrier, with means for automatically moving same toward and coupling same to said plate-carrier, means for automatically uncoupling same when it returns to the initial position, and automatic means for holding the card-carrier in the initial position until released, and an 120 ink-roller automatically operated by the motion of said plate-carrier for inking the plate, substantially as described.

33. In a plate-printing machine, the combination with a frame, a lower printing-roller 130

- journaled thereon, and an upper printing-roller mounted above said lower printing-roller, of a plate-carrier traveling on said frame between said rollers, and a card-carrier, 5 with means for automatically moving same toward and coupling same to said plate-carrier, means for automatically uncoupling same when it returns to the initial position, and automatic means for holding the card-carrier 10 in the initial position until released, with means for holding the card normally at an angle on said card-carrier and causing it to project above and clear of the plate, except when pressed between the rollers, and means 15 for inking the plate, substantially as described.
34. In a plate-printing machine, the combination with a frame, a lower printing-roller journaled thereon, an upper printing-roller mounted above said lower printing-roller, 20 clips on said upper roller, and a removable shell in the form of a segment of a cylinder secured by said clips to said upper printing-roller, of a plate-carrier mounted to vibrate on said frame between said rollers, an adjustable plate-holder mounted on said carrier, and means for feeding the card to the plate, substantially as described.
35. In a printing-roller for use in plate-printing machines, the combination with a cylindrical roller, of a shell in the form of a segment of a hollow cylinder and provided with reduced flanges adapted to fit on the surface of said roller, lugs projecting into said shell, and clips mounted on said roller and engaging 35 said flanges, substantially as described.
36. In an upper printing-roller for plate-printing machines, the combination with a cylindrical roller provided with lugs projecting from its surface and with clips, of a shell in 40 the form of a segment of a hollow cylinder provided with recesses to receive said lugs and with a flange to engage said clips, substantially as described.
37. In a printing-roller for plate-printing machines, the combination with a cylindrical roller, and a shell in the form of a segment of a hollow cylinder detachably connected thereto, with a curved metallic plate secured over the operative face of said segment, substantially as described.
38. In a printing-roller for use in plate-printing machines, the combination with a cylindrical roller, of a shell in the form of a segment of a hollow cylinder and provided with 55 reduced flanges adapted to fit on the surface of said roller, lugs projecting into said shell, and clips mounted on said roller and engaging said flanges, with a curved metallic plate secured over the operative face of said segment, 60 substantially as described.
39. In an upper printing-roller for plate-printing machines, the combination with a cylindrical roller provided with lugs projecting from its surface and with clips, of a segment 65 in the form of a hollow cylinder provided with

recesses to receive said lugs and with a flange to engage said clips, with a curved metallic plate secured over the operative face of said segment, substantially as described.

40. In a card-carrier for use in plate-printing machines, a device for holding the card normally at an angle to the horizontal and for releasing said card when desired, substantially as described. 70

41. In a card-holder for use in plate-printing machines, the combination with a spring-gripper adapted to hold the card normally at an angle with the horizontal, of means for throwing said gripper out of action and into action when desired, substantially as described. 75

42. A card-gripper for use in card-carriers for plate-printing machines, comprising a bar having an inclined groove cut therein, spring-clips normally pressing the edge of the card into said inclined groove, with means for withdrawing said clips from engagement with the card and for releasing said clips and allowing them to grip said card when desired, substantially as described. 80

43. A card-gripper for use in card-carriers for plate-printing machines, comprising a bar having an inclined groove cut therein, spring-clips normally pressing the edge of the card into said inclined groove, with automatic means for withdrawing said clips from engagement with the card, and means for releasing said clips and allowing them to grip said card when desired, substantially as described. 85

44. A card-gripper for use in card-carriers for plate-printing machines, comprising a bar having an inclined groove cut therein, spring-clips normally pressing the edge of the card into said inclined groove, with a spreader-bar for moving said clips from engagement with the card, and means for withdrawing said spreader-bar and releasing said clips and allowing them to grip said card when desired, substantially as described. 90

45. A card-gripper for use in card-carriers for plate-printing machines, comprising a bar having an inclined groove cut therein, spring-clips normally pressing the edge of the card into said inclined groove, means automatically operated by the motion of the card-carrier for moving said clips from engagement with the card, and means for releasing said clips and allowing them to grip said card when desired, substantially as described. 95

46. A card-gripper for use in card-carriers for plate-printing machines, comprising a bar having an inclined groove cut therein, spring-clips normally pressing the edge of the card into said inclined groove, a spreader-bar automatically operated by the motion of the card-carrier for moving said clips from engagement with the card, and means for withdrawing said spreader-bar, thus releasing said clips and allowing them to grip said card when desired, substantially as described. 100

47. A card-gripper for use in card-carriers for plate-printing machines, comprising a bar having an inclined groove cut therein, with means for adjusting said bar on the card-carrier, spring-clips normally pressing the edge of the card into said inclined groove, with automatic means for withdrawing said clips from engagement with the card, and means for releasing said clips when desired, thus allowing them to grip said card, substantially as described.

48. A card-gripper for use in card-carriers for plate-printing machines, comprising a bar having an inclined groove cut therein, with means for adjusting said bar on the card-carrier, spring-clips normally pressing the edge of the card into said inclined groove, with a spreader-bar for moving said clips from engagement with the card, and means for withdrawing said spreader-bar when desired, thus releasing said clips and allowing them to grip said card, substantially as described.

49. A card-gripper for use in card-carriers for plate-printing machines, comprising a bar having an inclined groove cut therein, spring-clips normally pressing the edge of the card into said inclined groove, a spreader-bar, a spring normally withdrawing said spreader-bar from engagement with said clips, means operated by the motion of the card-carrier for pressing said spreader-bar against the action of its withdrawing-spring beneath said clips, means for holding the spreader-bar in the advanced position, and means for releasing said spreader-bar when desired, thus releasing said clips and allowing them to grip said card, substantially as described.

50. In a card-carrier for plate-printing machines, the combination with a gripper-frame, with means for adjusting same laterally and angularly on said carrier, of a card-gripper, comprising a bar having an inclined groove cut therein, spring-clips normally pressing the edge of the card into said inclined groove, with a spreader-bar for moving said clips from engagement with the card, and means for withdrawing said spreader-bar when desired, thus releasing said clips and allowing them to grip said card, substantially as described.

51. A card-gripper for use in card-carriers for plate-printing machines, comprising a bar having an inclined groove cut therein, with means for adjusting said bar on the card-carrier, spring-clips normally pressing the edge of the card into said inclined groove, with automatic means for withdrawing said clips from engagement with the card, and means operated by hand for releasing said clips when desired, thus allowing them to grip said card, substantially as described.

52. A card-gripper for use in card-carriers for plate-printing machines, comprising a bar having an inclined groove cut therein, with means for adjusting said bar laterally and lon-

gitudinally on the card-carrier, spring-clips normally pressing the edge of the card into said inclined groove, with automatic means operated by the motion of the card-carrier for withdrawing said clips from engagement with the card, and means for releasing said clips when desired, thus allowing them to grip said card, substantially as described.

53. A card-gripper for use in card-carriers for plate-printing machines, comprising a bar having an inclined groove cut therein, spring-clips normally pressing the edge of the card into said inclined groove, a spreader-bar, a spring normally withdrawing said spreader-bar from engagement with said clips, means operated by the motion of the card-carrier for pressing said spreader-bar, against the action of its withdrawing-spring, beneath said clips, a catch for holding the spreader-bar in the advanced position, and means for withdrawing said catch when desired, thus allowing said spring to draw back said spreader-bar and release said clips, substantially as described.

54. A card-gripper for use in card-carriers for plate-printing machines, comprising a bar having an inclined groove cut therein, spring-clips normally pressing the edge of the card into said inclined groove, a spreader-bar, a spring normally withdrawing said spreader-bar from engagement with said clips, means operated by the motion of the card-carrier for pressing said spreader-bar against the action of its withdrawing-spring beneath said clips, a catch for holding the spreader-bar in the advanced position, and a hand-lever for withdrawing said catch when desired, thus allowing said spring to draw back said spreader-bar and release said clips, substantially as described.

55. In a plate-printing machine, the combination with a frame, a lower printing-roller journaled thereon, an upper printing-roller mounted above said lower printing-roller, and guide-rods extending across said frame between said rollers, of a plate-carrier traveling on said guide-rods, a plate-holder mounted on said carrier, a card-carrier, also traveling on said guide-rods, with means for automatically moving same toward and coupling same to said plate-carrier, and for uncoupling same and holding the card-carrier in the initial position until released, with a spring-gripper for holding the card normally at an angle on said card-carrier and causing it to project above and clear of the plate, except when pressed between the rollers, substantially as described.

56. In a plate-printing machine, the combination with a frame, a lower printing-roller journaled thereon, an upper printing-roller mounted above said lower printing-roller, and guide-rods extending across said frame between said rollers, of a plate-carrier traveling on said guide-rods, a plate-holder mounted on said carrier, a card-carrier also traveling on

said guide-rods, and an ink-roller automatically operated by the motion of said plate-carrier for inking the plate, substantially as described.

5 57. In a plate-printing machine, the combination with a frame, a lower printing-roller journaled thereon, an upper printing-roller mounted above said lower printing-roller, and guide-rods extending across said frame between said rollers, of a plate-carrier traveling on said guide-rods, a plate-holder mounted on said carrier, a card-carrier, also traveling on said guide-rods, means for holding the card normally at an angle on said card-carrier and causing it to project above and clear of the plate, except when pressed between the rollers, and an ink-roller automatically operated by the motion of said plate-carrier for inking the plate, substantially as described.

15 58. In a plate-printing machine, the combination with a frame, a lower printing-roller journaled thereon, an upper printing-roller mounted above said lower printing-roller, and guide-rods extending across said frame between said rollers, of a plate-carrier traveling on said guide-rods, a plate-holder mounted on said carrier, a card-carrier, also traveling on said guide-rods, and means for holding the card at an angle above said carrier, substantially as and for the purposes described.

25 59. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, means for moving said plate-carrier in reverse directions on said frame, a card-carrier, with means for automatically moving same toward and coupling same to said plate-carrier, and for automatically uncoupling same and holding the card-carrier in the initial position until released, and means for releasing the card-carrier when desired, substantially as described.

35 60. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, with means for moving said plate-carrier in reverse directions on said frame, a card-carrier, with spring-operated mechanism for automatically moving same toward said plate-carrier, means for coupling same to said plate-carrier, automatic means for uncoupling the two carriers and for holding the card-carrier back when it reaches the initial position, and means for releasing said card-carrier, when desired, substantially as described.

45 61. In a plate-printing machine, the combination with a frame, a lower printing-roller journaled thereon, and an upper printing-

50 roller mounted above said lower printing-roller, of a plate-carrier mounted to travel on said frame between said rollers, a plate-holder mounted on said carrier, means for moving said plate-carrier in reverse directions on said frame, a card-carrier, with means for automatically moving same toward and coupling same to said plate-carrier, and for automatically uncoupling same and holding the card-carrier in the initial position until released, means for releasing the card-carrier when desired, means for holding the card on said card-carrier and for releasing it when desired, substantially as described.

55 62. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, with means for moving said plate-carrier in reverse directions on said frame, a card-carrier, with spring-operated mechanism for automatically moving same toward said plate-carrier, means for coupling same to said plate-carrier, and automatic means for uncoupling the two carriers and for holding the card-carrier back when it reaches the initial position, means for releasing said card-carrier, when desired, and a spring-gripper for holding the card normally at an angle on said card-carrier and causing it to project above and clear of the plate, except when pressed between the rollers, substantially as described.

60 63. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, means controlled from one end of the machine for moving said plate-carrier in reverse directions on said frame, a card-carrier, with means also controlled from the same end of the machine as the plate-carrier for automatically moving same toward and coupling same to said plate-carrier, and for automatically uncoupling same and holding the card-carrier in the initial position until released, means for releasing the card-carrier when desired, and means for holding the card normally at an angle on said card-carrier and for releasing it when desired, substantially as described.

65 64. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, with means controlled from one end of the machine for moving said plate-carrier in reverse directions on said frame, a card-carrier, with spring-oper-

ated mechanism also controlled from the same end of the machine as the plate-carrier for automatically moving same toward said plate-carrier, means for coupling same to said plate-carrier, and automatic means for uncoupling the two carriers and for holding the card-carrier back when it reaches the initial position, means for releasing said card-carrier when desired, and a spring-gripper for holding the card normally at an angle on said card-carrier and causing it to project above and clear of the plate, except when pressed between the rollers, substantially as described.

65. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, a weight for moving said plate-carrier in one direction, and mechanism for moving said plate-carrier in the opposite direction on said frame, a treadle for setting said mechanism in operation, a card-carrier, with spring-operated mechanism for automatically moving same toward the plate-carrier, and a second treadle having a lug projecting through the first for putting in operation the mechanism for moving the card-carrier, substantially as described.

66. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, a weight for moving said plate-carrier in one direction, and mechanism for moving said plate-carrier in the opposite direction on said frame, a treadle for setting said mechanism in operation, a card-carrier, with spring-operated mechanism for automatically moving same toward the plate-carrier, and a second treadle having a lug projecting through the first for putting in operation the mechanism for moving the card-carrier, substantially as described.

67. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, a weight for moving said plate-carrier in one direction, and mechanism for moving said plate-carrier in the opposite direction on said frame, a treadle for setting said mechanism in operation, a card-carrier, with spring-operated mechanism for automatically moving same toward the plate-carrier, and a second treadle having a lug pro-

jecting through the first for putting in operation the mechanism for moving the card-carrier, means for coupling said card-carrier to said plate-carrier, and automatic means for uncoupling the two carriers and for holding the card-carrier back when it reaches the initial position, and a spring-gripper for holding the card normally at an angle on said card-carrier and causing it to project above and clear of the plate, except when pressed between the rollers, substantially as described.

68. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, a weight for moving said plate-carrier in one direction, and mechanism for moving said plate-carrier in the opposite direction on said frame, a treadle for setting said mechanism in operation, a card-carrier, with spring-operated mechanism for automatically moving same toward the plate-carrier, and a second treadle having a lug projecting through the first for putting in operation the mechanism for moving the card-carrier, with inking mechanism operated by the mechanism for moving the plate-carrier, substantially as described.

69. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, a weight for moving said plate-carrier in one direction, and mechanism for moving said plate-carrier in the opposite direction on said frame, a treadle for setting said mechanism in operation, a card-carrier, with spring-operated mechanism for automatically moving same toward the plate-carrier, and a second treadle having a lug projecting through the first for putting in operation the mechanism for moving the card-carrier, means for coupling said card-carrier to said plate-carrier, and automatic means for uncoupling the two carriers and for holding the card-carrier back when it reaches the initial position, with inking mechanism operated by the mechanism for moving the plate-carrier, substantially as described.

70. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, a weight for moving said plate-carrier in one direction, and mechanism for moving said plate-carrier in the opposite direction on said frame, a treadle for setting said mechanism in operation, a card-

carrier, with spring-operated mechanism for automatically moving same toward the plate-carrier, and a second treadle having a lug projecting through the first for releasing the card-carrier and thus putting in operation the mechanism for moving the card-carrier, means for coupling said card-carrier to said plate-carrier, and automatic means for uncoupling the two carriers and for holding the card-carrier back when it reaches the initial position, means for holding the card normally at an angle on said card-carrier and causing it to project above and clear of the plate, except when pressed between the rollers, with inking mechanism operated by the mechanism for moving the plate-carrier, substantially as described.

71. In a plate-printing machine, the combination with a frame, a lower printing-roller journaled thereon, and an upper printing-roller mounted above said lower printing-roller, of a plate-carrier mounted to travel on said frame between said rollers, a plate-holder mounted on said carrier, a weight for moving said plate-carrier in one direction, and mechanism for moving said plate-carrier in the op-

posite direction on said frame, a treadle for setting said mechanism in operation, a card-carrier, with spring-operated mechanism for automatically moving same toward the plate-carrier, and a second treadle having a lug projecting through the first for releasing the card-carrier and thus putting in operation the mechanism for moving the card-carrier, means for coupling said card-carrier to said plate-carrier, and automatic means for uncoupling the two carriers and for holding the card-carrier back when it reaches the initial position, a spring-gripper for holding the card normally at an angle on said card-carrier and causing it to project above and clear of the plate, except when pressed between the rollers, with inking mechanism operated by the mechanism for moving the plate-carrier, substantially as described.

In testimony whereof I affix my signature in presence of two witnesses.

JOSIAH PERCIVAL STEVENS.
